UNITED STATES PATENT OFFICE.

LAWRENCE LANGNER, OF NEW YORK, N. Y., ASSIGNEE TO THE DAYTON ENGINEERING LABORATORIES COMPANY, A CORPORATION OF OHIO.

MAGNETO.

1,314,197.

Specification of Letters Patent. Patented Aug. 26, 1919.

Original application filed September 22, 1913, Serial No. 790,968. Divided and this application filed September 21, 1917. Serial No. 192,506.

To all whom it may concern:

Be it known that I, LAWRENCE LANGNER, a subject of the King of Great Britain, residing at New York city, county of New

- 5 York, and State of New York, United States of America, have invented certain new and useful Improvements in Magnetos, of which the following is a full, clear, and exact description.
- 10 This invention relates to improvements in magnetos and has among its objects more particularly to provide an attachment for magneto machines which may be employed in connection with magnetos as placed upon
- 15 the market today by magneto manufacturers.

This application is a division of my application, Serial No. 790,968, filed September 22, 1913, patented Mar. 19, 1918, No.

20 1,259,529.

This device is so arranged that it may be attached to or detached from an ordinary magneto, and the attachment comprises auxiliary electro-magnetic windings for increasing the intensity of the magnetic flux of the machine.

Some preferred embodiments of the invention are illustrated in the accompanying drawings, in which:

30 Figures 1, 2 and 3 illustrate three forms of electro-magnetic attachment in end elevation, the parts being shown in section.

In Fig. 1, which shows a magneto of the well known Bosch type, I have shown a detachable device in the form of a frame or strap 21, preferably of magnetic material, which is adapted to fit over the permanent magnet 22 of the machine. This strap is bent around at each side thereof to form a housing 23 for a soft-iron core 24, and around this core and housing is arranged the winding 3. The terminals 25 of the winding 3 also serve for securing the attachment to the magneto. In Fig. 2 the detachable device is in the form of a non-magnetic brass strap 21^a, tied together at the upper end and bent to provide a housing

for the electro-magnet 3 which is maintained in said housing by means of pins 26, extending from the core 27 through holes 50 in the housing.

Instead of providing a separate core, I may form the strut 27^a of soft iron and bend it as shown in Fig. 3 to form the core.

The binding posts 25 may serve as points 55 of attachment for wires leading from any convenient auxiliary source of current, for energizing the windings 3 of the detachable electro-magnets.

In the parent case, of which the present 60 is a division, the auxiliary electro-magnets were energized by current from a battery in a system where the magneto is utilized as an ignition device, and the battery current lead into the auxiliary magnets as an accompaniment to the operation of starting the gas engine in which the ignition system is used.

This illustrates one advantageous mode of use of this detachable or auxiliary device for increasing the magnetism of the magneto under certain conditions.

The feature of the present application is that of having an attachable or detachable auxiliary set of electro-magnetic windings, which may be superposed upon and attached 75 to the magnets of an ordinary magneto, and thus be utilized as an auxiliary excitation to increase the magnetic flux of the magneto.

While the form of mechanism herein 80 shown and described constitutes a preferred form of embodiment of the invention, it is to be understood that other forms might be adopted, all coming within the scope of the claims which follow.

What I claim is:

1. In combination, a magneto including permanent magnets, with an attachment for increasing the intensity of magnetic flux of the magneto, said attachment being a unitary structure comprising a core, a winding for said core, and means for detachably securing said attachment to the magneto.

2. In combination, a magneto having per-

manent magnets, and an auxiliary electro-magnetic device for increasing the intensity of magnetic flux of the magneto, said device comprising a unitary structure adapted to be superposed upon the magnets of the magneto and detachably secured thereon, said structure being composed of a core ar-

ranged in parallel relation with the magnets and electro-magnetic windings mounted upon the core.

10

In testimony whereof I affix my signature.

LAWRENCE LANGNER.

Witness:

J. B. McGuire.
